(57) **CLAIM**

I claim the ornamental design for a double eyebolt for dental protruor, as shown and described.

DESCRIPTION

FIG. 1 is a perspective view of a double eyebolt for dental protruor in accordance with the present invention.

FIG. 2 is a left-side view of the double eyebolt for dental protruor of FIG. 1 shown at an enlarged scale.

FIG. 3 is a right-side view of the double eyebolt for dental protruor of FIG. 1 shown at an enlarged scale.

FIG. 4 is a front view of the double eyebolt for dental protruor of FIG. 1.

FIG. 5 is a rear view of the double eyebolt for dental protruor of FIG. 1.

FIG. 6 is a top view of the double eyebolt for dental protruor of FIG. 1; and,

FIG. 7 is a bottom view of the double eyebolt for dental protruor of FIG. 1.
